UNITED STATES PATENT OFFICE

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS

PATTERN MECHANISM FOR KNITTING MACHINES

Application filed January 5, 1931, Serial No. 506,609. Renewed December 7, 1931.

This invention relates to automatic knitting machines, and is concerned with devices for patterning motions of knitting instruments, including means for accurately transmitting motions from pattern surfaces to the things required to be operated by them, and especially to instruments necessarily subjected to movement in relation to the remainder of the machine.

10 One object of the invention is to provide for the motions of a cam selector finger or the like with sufficient accuracy to discriminate between closely spaced lugs, projections or specially formed faces of instruments which 15 are required to be selectively operated, and especially of such instruments as are required also to be moved, as an incident of the operation of the machine, into different operating planes. For example, it is well known in the 20 art of machine knitting automatically to determine and vary the length of stitch knit by knitting needles by moving the carrier for the needles (or instruments operating in and movable with the carrier) in relation to the 25 operative stroke of the needles; it is also well known in the art to interfere with the operation of knocking-over instruments, sinkers, or web holders for the purpose of affecting the stitches made by needles adjacent to 30 them; for instance, to determine a special stroke or special degree or time of advance of knocking-over instruments, web holders or sinkers at the verge of the needle carrier in relation to yarns fed for plating, to affect 35 the arrangement, or effect different arrangements, of the yarn in the throats of the needles.

In order to form a pattern by the aid of 40 movable instruments cooperating with the needles, it is necessary to determine a selection of these instruments. When, in a preferred instance, the web holders are the instruments interfered with for this purpose, and they are provided with steps, butts or 45 projections at several different levels, for the purpose of discriminating among the different web holders by a relatively fixed cam, the exigencies of space in the machines are such as to require accurate positioning of the instrument for operating on the web holder in

respect to the series of web holders, or other knocking-over instruments, which instruments are so small as to provide little room for accessible differentiated stepped edges or lugs. Another object of my invention therefore is to provide for the accurate motion of a cam for selection in respect to a series of instruments carried by the needle carrier in a knitting machine, and particularly to provide for relative motion for selection between the said instruments and the said cam or finger which shall be accurate, whatever may be the adjusted position or adjustment motions of the needle carrier for other operative purposes of the machine.

55 The invention will now be explained by the aid of a specific instance of application of my new device to machines of the well known Scott & Williams type made under the Robert W. Scott Patents No. 1,282,958, dated October 29, 1918; No. 1,641,101, dated August 30, 1927; No. 1,189,220, dated June 27, 1916; and No. 1,236,770, dated August 14, 1917.

60 In the drawings:

Fig. 1 is a left-side elevation of so much 75 of one of said machines as is necessary to explain the invention;

Fig. 2 is a detail plan above the web holder cam cap;

Fig. 3 is a typical detail radial section at 80 the verge of the needle cylinder; and

Fig. 4 is a diagram in plan showing one relation of yarn feed, normal web holder motions, and patterning web holder motions.

85 The machine to which the invention is applied as shown in the drawings may comprise any usual needle carrier 260, in the instance shown mounted for axial, rotatory and reciprocatory movements in respect to a bed plate D on a bearing at the top of a column 90 280. The machine may have the usual means for driving the cylinder 260 from the bevel gear 31 on a main shaft 32. Cylinder 260 may carry the usual web holder bed 295 for web holders 290, which are normally actuated by a web holder cam cap 300 held against rotation with the cylinder 260 and bed 295 by the usual means. The machine may have any suitable cylinder needle latch guard ring 95 550, and any desired means for feeding yarn 100

in proper relation to the needles, including means to feed at least two yarns in normal plating relation to each other.

The column 280 may as usual be adapted 5 to be vertically moved with respect to the remainder of the machine, for the purpose of changing the elevation of the needle carrier 260 and its attachments in relation to cams carried by a ring on the bed plate D, not 10 shown, and hence altering the stitch-length, according to the said Scott Patent No. 1,189-220. Alteration of the stitch-length may be pattern controlled in respect to carrying out this function at particular parts of the article 15 according to the said patents; as shown herein the operation is performed by the two-armed lever 281 on a fixed stud 450 reacting with a lug 286 on the column 280 to position the column and needle cylinder in a vertical 20 sense. One arm of the lever 281 takes against a ring of cams on a pattern drum 120 geared to a main pattern shaft 80, racking motion of which occurs from time to time as a consequence of indications on a primary pattern 25 surface, shown as the chain 60, on a sprocket continually driven by a ratchet 62, all as well known and shown in said patents.

The machine may also comprise an auxiliary pattern surface shown as a drum 71C 30 mounted on a shaft 711 and driven according to said Scott Patent No. 1,236,770 or the device of my application Serial No. 389,183, filed August 29, 1929, by a suitably controlled ratchet mechanism, not shown, actuation of 35 which may be predetermined as in said pattern surface 60, and suitable connections.

Referring now to Fig. 3, in order to discriminate among the web holders 290, for 40 example in order to cause selected members of the series 290 to be moved inwardly to an abnormal extent, or at an abnormal time in relation to the yarns fed and the depression of the needles by a stitch cam; or in order 45 to provide for abnormally positioning selected members of the series of web holders 290 in an abnormal forward position during or prior to their actuation, the web holders may be provided with a series of selector butts *w* 50 adapted to react with the cam finger *w*¹ on a radially placed bar *w*² mounted for vertical motion in respect to a standard 10 having a pin 11 adapted to take into a hole in the bar *w*². The bar *w*² and cam finger *w*¹ are vertically 55 moved to encounter one or the other series of the butts *w* according to the pattern to be knit. Referring to Fig. 4, when one of the butts *w* is encountered by cam finger *w*¹, the web holder is advanced, whereas normally 60 operated web holder butts travel at line *x*, *x* in relation to the needles *n*. The finger *w*¹ may operate anywhere between the usual wave of withdrawal by cams in cap 300 and the place of feeding the yarns *y*, *y*¹. As 65 shown, it is placed between the yarn feed

throat F and the advancing phases of the needles *n* at the stitch cam for circular knitting, not shown.

For rigidity the bar *w*² may be mounted on a block 12 fastened at the top to a vertical 70 rod 13 passing through a bore in a lug 14 of the standard 10. Preferably the bar *w*² is provided with a reinforcing piece 15 mounted on the block 12 by screws 16. Bar 13 may also have a bearing in a hole in a lug 17 of the standard 10 projecting over the edge of the bed plate D. Beneath the lug 17 a compression spring 18 reacting against a collar 19 resists upward motion of the rod 13 and bar *w*².

Preferably pattern motions of the bar *w*² and finger *w*¹ are derived from the auxiliary pattern surface constituted of the cams 712, of different heights corresponding to the 85 number of differently placed butts *w*, carried by the auxiliary pattern drum 710. As usual, the cam surface of the drum 710 transmits its indications to a depending indicator lever 800 rocking on a fixed stud 718. Lever 800 may have an arm 801 carrying an adjustable follower 802 for a cam formed on the end of the main pattern surface or drum 120, as shown at 803; this cam ring may normally hold the structure 800, 801, 803 upwardly out of position for contact with any part of the cam 90 indications on the surface 712, but in the position shown in Fig. 1 gaps in the cam ring 803 permit the lever 800 to swing its follower nose 805 into contact with the ring of cams 712. This occurs whenever pattern indications are to be transmitted to the selector cam finger *w*¹.

The cam finger *w*¹ is required to be positioned in respect to the lugs *w* on the web 95 holders 290 to react with one or the other superposed series in like position of the numerous butts *w*, shown as in series five in number, any one or more of which butts may be sheared off in order to cause the web holder having a removed butt not to be affected to 100 move out of path *x*, Fig. 4, when the finger *w*¹ is at any particular height. But this height is in respect to the web holders, which partake of the up and down motion of their bed 295 and the needle cylinder 260. It is therefore 110 required, since the vertical position of column 280 and needle cylinder 260 may vary more than the distance separating the web holder butts, to provide for transmitting the indications of the pattern surface 710, 712 to the bar *w*² and finger *w*¹ in such a way as to compensate for changes in the vertical position, within the necessary limits, of the series of web 120 holders.

One preferred way of doing this is to provide that the motion transmitted by the lever 800 shall have the same effect whatever the vertical position of the web holders, or whatever part is desired to be operated by the selector cam moved by the transmitting con- 130

nections. As shown, there may be provided on the column 280 a fixed pivot 25 for a bell crank lever having a vertical arm 26 connected by a substantially horizontal link 130 5 to a pin 131 on the lever 800; and having a substantially horizontal arm 27 connected by the link 28 to the collar 19 of the rod 13. Preferably, as shown, the connection of the link 28 with the collar 19 is adjustable by 10 the eccentric disk 132, the end of the link being slotted at 133 and loosely held on the collar 19 by a screw 134.

It will be observed that the position of the center 718 for the arm 800 is such as to 15 translate cam motions of the nose 805 into substantially horizontal motions of the link 130, whatever the change in position of the column 280, whereas vertical motion of the pivot 25 with the column 280 is transmitted 20 through arm 27 of lever 26, 27, the link 28 and rod 13 to the bar w^2 , which, with the cam finger w^1 , moves vertically in consonance with the motion of the column 280 and the needle cylinder 260. Therefore, whatever 25 the measured heights of the cams 712, the finger w^1 will be moved accordingly, whether or not the web holders are at any one of their operative heights. Horizontal movement of link 130 as produced by the pattern cams 30 712 thus varies the angle between the parts 27 and 28 and thereby changes the effective length of the chain of connections including the parts 27, 28 and 13 between the pivot 25 35 on and movable with column 280 and the bar w^2 , for the purpose of causing the finger w^1 to react with butts w in different planes in relation to the cylinder verge, whatever the position of column 280 and cylinder 260.

I claim:

40 1. Knitting machine having therein in combination means for knitting including needles and a series of cooperative instrumentalities adapted to be shifted in relation to the needles for a variation of the effect of the needles on the knit fabric being made, movable cam means reacting with said instrumentalities severally for operating upon them selectively to vary their cooperation with the needles, a pattern device, and connections from the pattern device to said cam, means for selectively positioning the latter, said connections being mounted independently of the pattern device and operative to 45 compensate for axial adjustment of the needle carrier, the connections comprising a part actuatable by the pattern device and movable in a path substantially perpendicular to the direction in which said series of instrumentalities are shifted.

50 2. Knitting machine having therein in combination means for knitting including needles and a series of cooperative instrumentalities adapted to be shifted longitudinally in relation to the needles for a variation of the effect of the needles on the knit fabric

being made, movable cam means reacting with said instrumentalities severally for operating upon them selectively to vary their cooperation with the needles, a pattern device, connections interposed between the pattern device and the cam and acting to position the cam selectively in response to indications of the pattern device, said connections being mounted independent of the pattern device and operative to compensate for 70 longitudinal movement of the needle carrier,

75 said connections comprising a lever, and a fulcrum for the lever arranged to partake of the longitudinal movement of the needle carrier.

80 3. Knitting machine having therein, in combination, means for knitting including a needle carrier and a series of knocking-over instruments at the carrier-verge adapted to be shifted longitudinally simultaneously in relation to the needles by motions of the needle carrier in respect to the needles, movable cam means reacting with said knocking-over instruments severally for positioning them 85 selectively to vary their cooperation with the needles, means for moving the needle carrier and knocking-over instruments longitudinally of the needles, a pattern device, connections interposed between the pattern device and the cam and acting to position the cam selectively in response to indications of the pattern device, said connections being operative to compensate for longitudinal movement of the needle carrier, the connections comprising a lever arm, a link disposed at an angle to said arm, and an element actuated by the pattern device to swing the lever and thereby change the angular relation of the link and lever.

90 4. Knitting machine having therein knitting devices and a series of instruments subject to alteration of position in respect to the remainder of the machine as an incident of normal operation, means for adjusting the position of said series of instruments, means for performing a selection among said instruments for a special function including a cam adapted to be positioned in one or another position according to a selection to be made; in combination with means including a link for moving said cam concomitantly with the positioning movements of said instruments, a pattern surface and means for advancing said surface at predetermined times, an indicator adapted to be moved by the pattern surface, and means for transmitting motions of said indicator to said link in any of the positions of said link and cam, said motion transmitting means comprising a part movable in a path substantially perpendicular to the direction of adjustment of said series of instruments.

105 5. In a knitting machine having a needle carrier, a web holder bed and a series of web holders adapted to be raised and lowered to 110 115 120 125 130

- alter the stitch length, a web holder selecting cam, a pattern surface, means independent of the pattern surface operative to raise and lower said cam concomitantly with motions of the needle carrier, and further means, responsive to indications of said pattern surface, for shifting said raising and lowering means whereby to cause selective motions of said selecting cam in respect to the series of web holders and their carrier.
6. In a knitting machine a needle carrier and needles movable therein, knocking-over instruments having selector butts mounted on said carrier for freedom of motion crosswise of the needles, and a selecting cam for the knocking-over instruments adapted to be moved in the direction of motion of the needles in their carrier for selection of different instruments for motion in respect to the needles; means for adjusting the needle carrier, knocking-over instruments and selecting cam together longitudinally of the needles, for alterations of stitch length; in combination with a pattern surface, and a transmitting link movable in a path substantially perpendicular to the path of adjustment of the needle carrier for reacting with the selector cam adjusting means to move the cam to different positions relatively to the knocking-over instruments to obtain different selections among the latter.
7. In a knitting machine having a frame and bed-plate and a needle-cylinder adapted for vertical motion in respect to said bed-plate for alteration of stitch length, a series of knocking-over instruments carried by the needle cylinder, said instruments having differentiated operating butts, a cam for actuating said instruments selectively in accordance with its vertical position in relation to the needle cylinder, in combination with means for mounting said cam on the bed-plate for vertical freedom of motion; a column supporting the needle cylinder, means operated by a movable main pattern surface for lifting and lowering the column; a bell-crank lever having horizontal and vertical arms pivoted on said column, and a link between said horizontal arm and cam; an indicator device having horizontal freedom of motion, a substantially horizontal link between said vertical arm and said indicator device; an auxiliary pattern surface in contact with said indicator device; and means to advance said auxiliary pattern surface from time to time whereby said cam is independently positioned according to the indications of each of said pattern surfaces to work selected knocking-over instruments.
8. A knitting machine having a needle carrier and a cam for selecting knitting instrumentalities in said carrier, in combination with pattern means for the selecting movements of said cam, said carrier having a movement relatively to said pattern means

and axial of itself, and a connection transmitting the selections of the pattern means to the cam with compensation for the axial movement of the carrier.

9. A knitting machine having pattern selecting means, a needle carrier with movement relative to said pattern means and axial of itself, and a cam for selecting knitting instrumentalities in said carrier, in combination with connections from said pattern selecting means to said cam having means to compensate for the axial movement of the carrier.

10. In a knitting machine having a circular instrument carrier and means for adjusting it in an axial direction, a knitting instrument movably mounted in said carrier, said instrument having a plurality of selecting butts disposed serially in a direction parallel to the axis of the carrier, a selector movable into engagement with any predetermined one of said butts, a pattern device fixed in space as respects axial movement of the carrier, and transmitting means operative to position the selector in operative relation to a selected instrument butt in accordance with an indication of the pattern device, said transmitting means comprising a part which partakes of the movement of the carrier and being constructed and arranged to compensate for movement of the carrier so that operation of the selector means is substantially unaffected thereby.

11. In a knitting machine having a movable carrier for knitting instrumentalities, a knitting instrumentality movably mounted in said carrier, said instrumentality having a plurality of selecting butts, means for moving the carrier lengthwise of said series of selecting butts, a selector device movable into engagement with any predetermined butt of said instrumentality, pattern means fixed in space as respects movements of said instrument carrier, and means for transmitting motion from the pattern means to the selector device, said transmitting means being operative to compensate for adjustments of the carrier so that operation of the selector device in response to pattern indications is substantially unaffected by such adjustment of the carrier.

12. A knitting machine having a movable needle carrier, knitting instrumentalities movable with the carrier, and a movable cam for selectively controlling said knitting instrumentalities, in combination with pattern means for determining the movements of the cam, means for adjusting the needle carrier in a direction longitudinally of the needles and relatively to the pattern means, and connections for transmitting selective determinations of the pattern means to the cam, said transmitting connections being operative to compensate for adjustments of the needle carrier.

13. A knitting machine having pattern means, a circular needle carrier, knitting instrumentalities movable with the carrier, means for adjusting the carrier in an axial direction and relatively to the pattern means, a cam for selecting knitting instruments, in combination with connections from the pattern means to the cam compensating for axial adjustments of the needle carrier. 70
14. A knitting machine having a circular instrument carrier, a knitting instrumentality mounted on the carrier, a selector device movable axially of the carrier into any of a plurality of predetermined positions and operative to affect the action of said knitting instrumentality differently in accordance with the position of the selector device, means for adjusting the carrier axially, a pattern device fixed in space as respects said adjustment of the carrier, and means for transmitting movement of the pattern device to the selector device, said transmitting means being constructed and arranged to compensate for adjustments of the carrier. 80
15. In a knitting machine having a movable needle carrier and pattern-controlled means for moving it longitudinally of the needles, the combination of a cam for working instruments at the needle verge, a pattern device carried by a part of the machine which does not partake of the longitudinal movement of the needle carrier, and connections interposed between said pattern device and the cam and adapted to position the cam in accordance with selective indications of the pattern device, said connections being mounted independently of the pattern device and operative to compensate for longitudinal adjustment of the needle carrier. 90
16. In a knitting machine having a movable needle carrier and pattern-controlled means for moving it longitudinally of the needle, the combination of a cam for working instruments which are movable with the needle carrier, a series of instruments having differentiated operating butts in said carrier, a pattern device carried by a part of the machine which is normally fixed as respects pattern-controlled longitudinal movement of the needle carrier, and connections interposed between said pattern device and the cam and acting to position the cam in accordance with selective indications of the pattern device, said connections being mounted independently of the pattern device and operative to compensate for longitudinal adjustment of the needle carrier, said connections comprising a part which partakes of the longitudinal movement of the needle carrier. 100
17. In a knitting machine a needle carrier and needles movable therein, knocking-over instruments having selector butts mounted on said carrier for freedom of motion cross-wise of the needles and a selecting cam for the knocking-over instruments adapted to be moved in the direction of motion of the needles in their carrier for selecting different instruments for motion in respect to the needles, means for adjusting the needle carrier, knocking-over instruments, and the selecting cam concomitantly longitudinally of the needles for alteration of stitch length, in combination with a pattern surface mounted upon a part of the machine other than the needle carrier, connections mounted independently of the pattern surface, said connections comprising an element mounted on and partaking of the movement of the means for adjusting the needle carrier, and a part responsive to indications of said pattern surface and operative to shift said connections whereby to alter the relation between said selecting cam and said knocking-over instruments, and means for moving said pattern surface. 110
18. A knitting machine having therein, in combination, a movable needle carrier, a series of instruments supported by the needle carrier, a primary pattern surface, a main pattern surface controlled by said primary pattern surface, an auxiliary pattern surface controlled by said primary pattern surface, means for altering the level of said series of instruments in response to indications of said main pattern surface, the auxiliary pattern surface being supported by a part of the machine which does not change its position when the level of said instruments is altered, a selector cam for said instruments, and means for moving said cam in response to changes of level of said instruments, connections operated by said auxiliary pattern surface for independently changing the level of said selector cam in respect to said instruments for performing a selection among them, and means having an element moving with said main pattern surface for preventing, at times, the actuation of said connections by the auxiliary pattern surface without interruption of the normal movement of the latter. 120
